(57) **CLAIM**

The ornamental design for a smart waste bin sensor, as shown and described.

DESCRIPTION

FIG. 1 is a front elevation view of a smart waste bin sensor showing our new design;

FIG. 2 is a rear elevational view thereof;

FIG. 3 is left side elevational view thereof, the right side elevational view being mirror image;

FIG. 4 is a top plan view thereof, the bottom plan view being mirror image; and,

FIG. 5 is a perspective view thereof.

The broken line showing is included for the purpose of illustrating portions of the “article” and forms no part of the claimed design.
